UNITED STATES PATENT OFFICE.

CLARENCE H. ORR, OF PROVIDENCE, RHODE ISLAND.

DESIGN FOR A SIGN PLATE.

Application filed July 14, 1925. Serial No. 14,084. Term of patent 3½ years.

To all whom it may concern:

Be it known that I, CLARENCE H. ORR, a citizen of the United States of America, residing at Providence, county of Providence, State of Rhode Island, have invented a new, original, and ornamental Design for a Sign Plate, of which the following is a specification, reference being had to the accompanying drawing, forming a part thereof.

The figure is a perspective view of a sign plate, showing my new design.

I claim:

The ornamental design for a sign plate, substantially as shown.

CLARENCE H. ORR.
